CARTON

Clarence W. Vogt, Saugatuck, Conn., assignor, by
mesne assignments, to Owens-Illinois Glass
Company, Toledo, Ohio, a corporation of Ohio

Application September 26, 1936, Serial No. 102,683

6 Claims. (Cl. 229—51)

The present invention relates to cartons of that type in which the closure is formed by foldable flaps, and the invention involves certain new and useful improvements in the closure flaps.

As a feature of the present invention, one or more of the closure flaps may be provided with easily severable portions which, when in closed position, may be severed from the main portion of the flaps by simple finger manipulation to effect easy opening of the carton.

As another feature of the invention, one or more flaps is provided with easily severable portions and the flaps are so constructed as to permit the fastening of a staple onto said severable portion to hold the flaps in closure position.

As a further feature, the outer closure flaps are provided with hingeable cut-outs which may be bent inwardly to lock the inner closure flaps in closed position after the carton has been opened.

In the shipment and storage of cartons, it is customary to have a number of these cartons closely packed together in a box or other container so that it is difficult or impossible to grasp the carton and pull it out from the container.

As a feature of the present invention, one or more of the closure flaps is provided with means whereby the carton may be grasped at one end and pulled out endwise from a close pack, said means also serving to form a lock to hold the inner closure flaps in closed position after the carton has been opened and reclosed. During transportation, this means is confined within the general outline of the carton so as not to interfere with the proper end to end stacking of the cartons.

Various other objects, features and advantages of the invention will be apparent from the following particular description and from an inspection of the accompanying drawing in which:

Fig. 1 is a plan view of the upper end of a blank for a carton embodying the present invention.

Fig. 2 is a perspective of the upper end portion of a carton embodying the present invention, and shows said carton fully open, and in conjunction with an inner flexible bag.

Fig. 3 is a view similar to Fig. 2 but showing the inner flaps folded into closure position.

Fig. 4 is a similar view but showing the flaps in closed and locked position and ready to be shipped.

Fig. 5 is a section taken on the line 5—5 of Fig. 4.

Fig. 6 is a view similar to Figs. 3 and 4 but shows a portion of the outer flaps broken away as a preliminary step in the opening of the carton.

Fig. 7 is a similar view but showing the outer flaps as used to lock the inner flaps in closed position after the carton has been opened and reclosed, and

Fig. 8 is an end view of the bottom of the carton showing the flaps which may there be used.

In the specific form illustrated, the carton is formed from a blank which is made of comparatively rigid material such as cardboard, and which has a series of longitudinally extending score or crease lines 11 along which the blank is folded to form the four side walls of the carton, and the usual comparatively narrow side flap 12 by means of which the opposite sides of the blank may be secured together to form a tubular carton of rectangular cross-section.

The four sections of the blank are provided with extensions, two of these forming the inner opposed flaps 13 and 14, and the other two forming the outer opposed flaps 15 and 16. All of these extensions are foldable in the usual manner along the crease or score line 18 extending transversely of the blank.

The inner flaps 13 and 14 are rectangular in shape and are long enough to overlap each other when folded inwardly across the upper end of the carton as shown in Fig. 3.

The flap 13 may, in some cases, be employed as a pouring spout, or if an inner bag be employed it may be directly secured to the flap or a pouring portion of the bag. In either case, it is preferable that this flap and the carton wall to which it is connected be provided with one or more scored lines, facilitating bending of the flap and the wall when the flap is in the same plane as the wall. As shown, there are provided two of these fold lines 10 extending from intermediate of the outer edge of the flap, across the score line 18, to the score lines 11 at opposite edges of the carton wall carrying the flap 13. By squeezing the carton by applying pressure on opposite sides of the carton adjacent to the upper ends of these last mentioned score lines, the wall and the flap may be bent to form a pouring spout or to facilitate opening up the inner bag if such bag be employed.

The inner closure flap 14 is provided with a pair of opposed weakened lines 20 and a weakened line 21 extending between said weakened lines 20 but spaced from the ends thereof to form a rectangular flap section 22 which may be easily severed or detached from the main body of said inner flap 14. The weakened lines may be formed by partial slitting or scoring or by a row of short slits or perforations.

The opposed outer closure flaps 15 and 16 are

of similar shape and construction, each having a base portion 23 which is preferably frusto-conical in shape, and a substantially rectangular tongue 24 of reduced width, extending from the outer end of said base portion 23. Each tongue 24 is rendered easily severable from the base portion 23 of the flap of a weakened line 25. Each base portion 23 is slit to form a hinged cut-out tongue 27 which is preferably frusto-conical in shape, with its wider free end adjacent to the score line 18. These tongues may be bent out of the plane of the main portion for the purposes hereinafter referred to.

The carbon of the present invention may be used to contain solids in powder, granular or other form, such as salt, sugar or the like, or may be used in conjunction with an inner flexible bag to hold liquid, powders or other material. In Fig. 2, the carton is shown in conjunction with an inner flexible bag 28 which forms no part of the present invention, and which may be combined with the carton in a manner shown and described in my copending application Serial No. 102,682, filed September 26, 1936.

In Fig. 2, the carton is shown set up in open position and the bag is shown filled and having an upper portion defining a head space which, after the completion of the filling operation, may be folded within the confines of the opposing panels of the carton.

In Fig. 3 is shown the initial closing step of the carton in which the inner flaps 13 and 14 are folded across the top of the carton in closure position, the flap 14 overlapping the flap 13. The two outer closure flaps 15 and 16 are then folded over the two inner closure flaps 13 and 14, and a wire stitch or staple 29 is applied through the two severable tongues 24 and through the severable flap section 22 as shown in Figs. 4 and 5. This stapling operation is effected while a suitable backing plate or a suitable grooved clincher plate extends between the two inner closure flaps 13 and 14, so that the ends of the staple will turn inwardly underneath the severable flap section 22 and above the flap 13 as shown in Fig. 5. The filled package as shown in Fig. 4 is then in condition to be stored or shipped.

In order to open the carton for dispensing purposes, the two tongues 24 are jointly held by the fingers and pulled to effect rupture thereof along the weakened lines 25. In this operation, the tongues 24 carry with them the flap section 22 stapled or otherwise secured thereto, and said section is likewise torn off. The parts will then be in the position and condition shown in Fig. 6. All of the flaps may then be lifted to open the carton, and the contents of the package may be dispensed either from the pouring spout of the bag 28 or from the carton itself if no inner bag is present, or in any other way.

After the desired amount of the contents of the package has been removed or dispensed, the two inner flaps 13 and 14 may be reclosed across the top of the carton, and held in closed position by merely pushing the tongues 27 inwardly and across the two inner flaps 13 and 14 as shown in Fig. 7. These tongues, in this position, will hold the inner flaps in closed position until it is desired to again remove or dispense another portion or the remainder of the contents of the package.

In the shipment and storage of containers, it is customary to have a number of these containers closely packed together so that it is difficult or impossible to grasp the side of a con-

tainer and pull it out from a pack. However, in the construction shown, one or both of the tongues 27 may be bent downwardly from the plane of the top of the carton as shown in Fig. 4 to form an opening through which a finger may be inserted for gripping the upper edge of a side wall and lifting the carton endwise from the close pack.

The bottom of the carton may be provided with any suitable form of closure flaps which may be sealed or secured together by interlocking projections or by staples, stitching or adhesive. Preferably, the bottom is formed as shown in Fig. 8. Two of the side walls of the box have rectangular flaps 30 and 31 which may overlap, and the other two side walls may have flaps 32 and 33 of such length that they exactly or substantially abut when in closed or folded position. The flaps 32 and 33 may be very much narrower at their free ends if desired. As shown, they are cut away on diagonal lines along each edge. The flaps 30, 32 and 33 may be secured together by a staple 34 or wire stitch or stitching, or in some instances by adhesive. If the staple or wire stitching is employed, a backing plate or clincher plate may be slid over the flap 31 and beneath the flap 30 to clinch the staple or wire and prevent it from entering the flap 31. As the staple or stitch is disposed above the flap 13 on the top, and below the flap 31 on the bottom, it will be obvious that if the carton be used in connection with any thin flexible inner bag or liner, the latter is protected from contact with the staple, stitch or other flap securing means.

Having thus described my invention, what I claim as new and desire to secure by Letters Patent is:

1. A carton having at one end a pair of rectangular opposed inner overlapping closure flaps and a pair of outer opposed closure flaps, one of said first pair of flaps having an easily severable portion at its outer end, and each of said latter extensions having an easily severable portion at its outer end overlapping said first mentioned easily severable portion and means for securing said severable portions together, whereby they may be removed as a unit.

2. A carton including a pair of opposed inner closure flaps overlapped along the full width at their outer ends and a pair of opposed outer closure flaps of such length that they do not overlap, each of said outer closure flaps being provided at its outer end with an easily severable tongue, and a fastener separately securing said tongues to the outer end of one of said first mentioned flaps.

3. A carton including a pair of opposed inner closure flaps and a pair of opposed outer closure flaps, each of said outer closure flaps being provided at its end with an easily severable tongue of reduced width, and one of said inner flaps having an easily severable portion directly underlying said tongues and means for securing together said tongues and said last mentioned severable portion whereby all of said readily severable portions may be torn from their respective flaps by a single manual operation when in closed position, to permit outfolding of all of the flaps.

4. A carton including a pair of inner closure flaps and a pair of outer closure flaps, each of said outer closure flaps being provided with a hinged cutout near the base thereof which may be folded inwardly out of the plane of said outer

closure flap to hold said inner closure flaps in closed position.

5. A package including a carton having at one end a pair of opposed inner closure flaps and a pair of opposed outer closure flaps, one of said inner closure flaps having an easily severable section at its outer end, and each of said outer closure flaps having an easily severable section at its outer end overlapping said first 10 mentioned severable section, and a staple interlocking all of said severable sections, whereby upon tearing off of the staple connected parts the remaining portions of the flap may be folded upwardly and outwardly to open the carton.

6. A carton including a pair of inner closure flaps and a pair of outer closure flaps, each of said outer closure flaps being provided with a hinged cutout section near the base thereof which may be folded inwardly out of the plane 5 of said outer closure flap to hold said inner closure flaps in closed position when the outer flaps are in upstanding position and one of said sections being sufficiently large to form a hole through which a finger may be inserted for lifting purposes when the outer flaps are in closed position. 10
